Primary Examiner — Sandra Snapp*Assistant Examiner* — Ieisha Price(74) *Attorney, Agent, or Firm* — Quickpatents, LLC;
Kevin Prince(57) **CLAIM**The ornamental design for a bullet lug nut cap, as shown and
described.

DESCRIPTION

FIG. 1 is a front elevation view of the bullet lug nut cap
showing our new design with the rear elevation views being
a mirror image of;

FIG. 2 is a top plan view thereof;

FIG. 3 is a bottom plan view thereof;

FIG. 4 is a top, side perspective view thereof;

FIG. 5 is a second top, side perspective view showing the
opposite side of FIG. 4;

FIG. 6 is a bottom, side perspective view thereof;

FIG. 7 is a second bottom, side perspective view showing
the opposite side of FIG. 6; and,FIG. 8 is a section cut view, taken along lines 8-8 of FIG. 2.
The broken lines in the drawings illustrate portions of the
bullet lug nut cap and form no part of the claimed design.**1 Claim, 4 Drawing Sheets**(56)
